[57] CLAIM

The ornamental design for a chair, as shown and de-
scribed.

DESCRIPTION

FIG. 1 is a front elevational view of a first embodiment
of a chair incorporating our new design;
FIG. 2 is a side elevational view of the first embodiment;

FIG. 3 is a top view of the first embodiment;
FIG. 4 is a rear elevational view of the first embodiment;

FIG. 5 is a bottom view of the first embodiment;
FIG. 6 is a front elevational view of a second embodiment
of a chair incorporating our new design;

FIG. 7 is a side elevational view of the second embodiment;
FIG. 8 is a top view of the second embodiment;

FIG. 9 is a rear elevational view of the second embodiment;

FIG. 10 is a bottom view of the second embodiment;
FIG. 11 is a front elevational view of a third embodiment
of a chair incorporating our new design;
FIG. 12 is a side elevational view of the second embodiment;

FIG. 13 is a top view of the third embodiment;
FIG. 14 is a rear elevational view of the third embodiment;

FIG. 15 is a bottom view of the third embodiment;
FIG. 16 is a front elevational view of a fourth embodiment
of a chair incorporating our new design;

FIG. 17 is a side elevational view of the fourth embodiment;
FIG. 18 is a top view of the fourth embodiment;

FIG. 19 is a rear elevational view of the fourth embodiment; and

FIG. 20 is a bottom view of the fourth embodiment.
